SCREW DRIVER

Norbert Schelot and Elmer E. Vahle,
St. Louis, Mo.

Application October 22, 1936, Serial No. 107,093

3 Claims. (Cl. 279—79)

This invention relates to screw drivers especially adapted for driving tempered screws into metallic bodies and has for the primary object the provision of a device of this character where-
5 in the bit thereof is of a tempered material and adjustable and removable from the device so that as the bit wears it may be advanced into working position and when worn to an extent to ren-
der it unfit for further use will be automatically
10 released to permit the placing in the device of a new bit of a similar construction.

With these and other objects in view, this invention consists in certain novel features of construction, combination and arrangement of
15 parts to be hereinafter more fully described and claimed.

For a complete understanding of our invention, reference is to be had to the following description and accompanying drawing, in which

20 Figure 1 is a fragmentary side elevation illustrating a screw driver constructed in accordance with our invention.

Figure 2 is a view similar to Figure 1, only partly in section, showing the head of the holding device for the bit.

Figure 3 is a vertical sectional view illustrating the device.

Figure 4 is a sectional view taken on the line 4—4 of Figure 1.

30 Figure 5 is a plan view illustrating a bit or blade.

Referring in detail to the drawing, the numeral 1 indicates an externally screw threaded body of cylindrical formation, one end (not shown) 35 is constructed to fit a chuck of a power driven tool or if desired may be secured in a handle. Mounted on the other end of the body and secured thereto by a pin 2 is a head 3 of sub-
stantially spherical shape provided with oppo-
40 sitely disposed beveled faces 4 and a flat face 5. The body 1 has a slot 6 extending therethrough and opening outwardly through the last-named end of the body or the end on which the head 3 is mounted. The flat face 5 of the head has a
45 slot aligning with the slot 6. Mounted in the slot 6 and protruding therefrom by way of the slot in the face 5 of the head is a bit or blade 7 having a work-engaging end 8 and oppositely arranged notches 9 located adjacent the other end thereof. The work engaging end of the bit or blade protrudes outwardly of the head 3 and the opposite end of the blade is engaged by a key or follower 10, the ends of which are forked, as shown at 11, and receive therein a substan-
50 tially U-shaped strap element 12, the ends of which are bent angularly to engage the notches 9 and the bight portion 13 thereof extends through the slot and engages with a nut 14 threaded on the body. The strap 12 engages
55 with one end of the nut and the key or follower

engages the other end of the nut. A lock nut 15 is threaded on the body to hold the strap against the nut 14.

In operation, as the working end 8 of the bit or blade wears from use the latter may be advanced outwardly of the head by adjusting the nut 14 on the body and when the bit or blade is worn to an extent that it is unfit for further use the angularly disposed ends of the strap 12 will ride on the curved faces of the head 3 and thereby become disengaged from the notches 9 and permit the bit or blade to pass freely from the slot 6.

Having described the invention, we claim:

1. A screw driver comprising a body having one end constructed to fit a tool chuck and provided with a slot opening outwardly through the opposite end thereof, a bit received in said slot and protruding therefrom at said last-named end of the body, a nut threaded on the body, said bit having notches, a substantially U-shaped strap engageable with the nut and extending through the slot and having its ends bent angularly to engage in the notches, a follower engaging the nut and the bit and having forked ends to receive the strap. 15

2. A screw driver comprising a body having one end constructed to fit a tool chuck and provided with a slot opening outwardly through the opposite end thereof, a bit received in said slot and protruding therefrom at said last-named end of the body, a nut threaded on the body, said bit having notches, a substantially U-shaped strap engageable with the nut and extending through the slot and having its ends bent angularly to engage in the notches, a follower engaging the nut and the bit and having forked ends to receive the strap, and a second nut threaded on the body to force the strap against the first-named nut. 20

3. A screw driver comprising a body having one end constructed to fit a tool chuck and provided with a slot opening outwardly through the opposite end thereof, a bit received in said slot and protruding therefrom at said last-named end of the body, a nut threaded on the body, said bit having notches, a substantially U-shaped strap engageable with the nut and extending through the slot and having its ends bent angularly to engage in the notches, a follower engaging the nut and the bit and having forked ends to receive the strap, a second nut threaded on the body to force the strap against the first-named nut, and a substantially spherical shaped head secured to the body to be engaged by the angularly related ends of the strap when said bit is substantially advanced outwardly of the body for disengaging said ends of the strap from the bit. 35
